[57] CLAIM

The ornamental design for a drawer insert for a desk storage tray system, substantially as shown and described.

DESCRIPTION

FIG. 1 is a top plan view of a drawer insert for a desk storage tray system, showing my new design;

FIG. 2 is a bottom plan view thereof;

FIG. 3 is an elevational view of the right side thereof;

FIG. 4 is an elevational view of the left side thereof;

FIG. 5 is a front elevational view thereof;

FIG. 6 is a rear elevational view thereof; and

FIG. 7 is an enlarged scale top perspective view thereof.

FIG. 1.

FIG. 3.

FIG. 2.

FIG. 4.

FIG. 5.

FIG. 6.

FIG. 7.
